(57) **CLAIM**

The ornamental design for a tank refill stand, as shown and described.

DESCRIPTION

FIG. 1 is a perspective view of a tank refill stand, showing my new design;

FIG. 2 is a further perspective view thereof;

FIG. 3 is a front elevational view thereof, the rear elevational view being a mirror image of the front elevational view; FIG. 4 is a left side elevational view thereof, the right side elevational view being a mirror image of the left side elevational view;

FIG. 5 is a top plan view thereof;

FIG. 6 is a bottom plan view thereof;

FIG. 7 is a further perspective view thereof, wherein the tank refill stand is shown with a corresponding fuel tank and refill components; and,

FIG. 8 is an additional perspective view thereof, wherein the tank refill stand is shown with a corresponding fuel tank and refill components.

The broken lines in FIGS. 1-8 are for the purpose of illustrating portions of the tank refill stand and environmental structure that form no part of the claimed design.
